BUFFING MACHINE

Norwood H. Knowlton, Rockport, Mass., assignor
to United Shoe Machinery Corporation, Borough
of Flemington, N. J., a corporation of New
Jersey

Application October 4, 1937, Serial No. 167,140

17 Claims. (Cl. 51—74)

This invention relates to buffing machines and is herein illustrated and described as embodied in a machine for buffing soles on their grain surfaces prior to their attachment to shoes. In the performance of this operation it is important to avoid visible scratch marks resulting from the action of individual particles of abrasive upon the surface of the work. It is important also to avoid what are known as waves or ripple marks which frequently occur in series parallel to the axis of the buffing roll. The two principal causes of these ripple marks are the vibration or whipping of soles fed tangentially past the buffing roll and the successive impacts of bulges on the buffing roll. In order to obtain a desirable finish it is necessary that the buffing be of uniform depth without anywhere cutting through the grain surface. The fact that the soles to be treated may have skived or beveled margins and other local inequalities of thickness renders it difficult to obtain a uniform buffing action.

It is an object of the invention to provide an improved buffing machine capable of meeting the requirements above referred to. In accordance with a feature of the invention there is provided a feeding mechanism comprising a plurality of driven rotary feed members spaced lengthwise of the buffing roll and arranged to hold a work-piece against the roll, in combination with a support for maintaining the axes of the feed members substantially parallel to each other in a plane parallel to the axis of the buffing roll and in a direction inclined to the axis of the buffing roll. The feed members of the illustrated machine consist of belts running over individual pulleys which are carried in a frame pivotally mounted for swinging movement, the frame being acted upon by springs to cause the pulleys to press the work-piece against the buffing roll. By inclining the direction of feed the work is given a component of movement lengthwise of the buffing roll, which component serves to prevent any individual particle of the abrasive from deepening and extending indefinitely with each succeeding contact the mark originally formed by it, and will cause the successive contacts of the particle to be displaced laterally from each other to form a series of relatively short shallow parallel lines which are relatively inconspicuous. Moreover, the lateral displacement of the work-piece resulting from this component will subject scratch marks already formed to the erasing action of the adjacent normal particles of abrasive.

In accordance with a further feature, means are provided for prolonging the engagement of

the work-piece with the buffing roll to effect a continued buffing action. This is accomplished by guide members which deflect the work-piece from its normal path of tangency and curve it about the buffing roll, holding it against the buffing roll with a pressure less than that of its initial engagement. This lighter continued buffing operation not only avoids the formation of ripple marks but serves still further to erase any scratch marks which might otherwise be visible.

These and other features of the invention will appear more fully from the following detailed description when read in connection with the accompanying drawings and will be pointed out in the appended claims.

Referring now to the accompanying drawings,

Fig. 1 is a view in end elevation of the improved machine;

Fig. 2 is a view in front elevation of the machine shown in Fig. 1;

Fig. 3 is a plan view of the machine;

Fig. 4 is an end view partly in section of the instrumentalities for imparting a transverse curvature to the soles and for presenting the soles to the buffing roll;

Fig. 5 is a plan view of the parts shown in Fig. 4;

Fig. 6 is a view in front elevation of the parts shown in Figs. 4 and 5;

Fig. 7 is a view in front elevation of the mechanism for pressing the work against the buffing roll and for feeding the work with a lengthwise component relatively to the buffing roll;

Fig. 8 is a plan view of a portion of the mechanism shown in Fig. 7;

Fig. 9 is a plan view of the mechanism for guiding and cleaning the work-pieces after their engagement with the buffing roll;

Fig. 10 is a view in end elevation of the mechanism shown in Fig. 9;

Fig. 11 is a sectional view illustrating passage of a work-piece past the buffing roll;

Fig. 12 is a detail view of the gear mechanism for driving the distorting rolls; and

Fig. 13 is a detail view of the gear mechanism for driving the cleaning brush and its associated feed rolls.

Before proceeding with a detailed description of the machine it should be noted that the soles, if skived, are first presented to a mechanism for distorting them transversely to impart to them a slightly bowed or arched form. The soles are fed lengthwise through this distorting mechanism and then against a buffing roll. Because of the slight transverse curvature of the soles their

marginal portions tend to bear against the buffing roll with a pressure which compensates at least in part for the reduction of pressure resulting from the relative thinness of the skived marginal portions. After passing the buffing roll the soles are cleaned by a rotary brush.

The supporting structure for the various mechanisms above mentioned is in the form of a frame comprising a column 10 (Figs. 1 and 2) having a base 12 adapted to rest upon the floor. Carried by the upper portion of the column 10 is a head comprising a horizontal plate 14 (Figs. 2 and 3) which is secured upon the top of the column 10, a vertical transversely extending flange 16 and a vertical flange 18 extending forwardly and rearwardly, all of which parts may be integral. Secured against the outer face of the flange 18 is a flat plate 20 (Figs. 1 and 3). Secured to the plate 20 by a pair of screws 22 which are threaded into the forward edge of the plate 20 is a vertical plate 24 having a large opening in its central portion. The plate 24 extends transversely and is positioned directly below the web 16. The outer or right-hand end of the plate 24, as seen in Fig. 2, is supported by a post 26 (see Fig. 1) the lower end of which is secured to the base 12 of the frame of the machine. The outer edge of the plate 24 is also secured to the flange 16 by an upright bar 27. The various parts 10, 12, 14, 16, 18, 20, 24, 26 and 27 all constitute a rigid frame structure.

The mechanism for distorting the sole is carried by a frame, indicated generally on Figs. 1, 3 and 4 by the numeral 28, comprising a pair of parallel vertically disposed plates 30 and 32 (Figs. 5 and 6) connected to each other by parallel crosspieces 34 and 36. Each of the plates 30 and 32 is provided with a flanged supporting foot 38 which extends over the upper edge of the plate 24 and is secured against the face of the plate 24 by a clamping screw 40 extending through a vertical slot provided in the foot for heightwise adjustment. Vertically disposed adjusting screws 42 are threaded into horizontal flanges in the feet and bear against the upper edge of the plate 24. A third foot 44 extends from the end plate 30 and is provided with a vertical slot through which extends a clamping screw 46 threaded into the face of the plate 24 to provide a third point of support for the frame 28. Journaled in ball bearings 48 in the plate 30 and in similar ball bearings in the plate 32 is a shaft 50 driven by a worm gear 52 secured upon an end of the shaft 50. The gear 52 is driven by a worm 54 secured upon a shaft 56 which is journaled in a casing 58 having a pair of ears 60 (one of which is shown in Fig. 4) by which the casing 58 is secured against the outer surface of the end plate 32. The shaft 56 is driven by a pulley 62 secured thereupon, the pulley 62 being itself driven through a belt 64 by means later to be described. The casing 58 is provided with cover plates 64 and 66.

It should be observed that the plate 32 (Figs. 3 and 5) is longer than the plate 30 and that the two plates extend parallel to each other not at right angles to but at angles of 85° from the plate 24. The axis of the shaft 50 is inclined in a horizontal plane at an angle of 5° from the surface of the plate 24 or, more generally speaking, at an angle of 5° to the transverse horizontal center line of the machine. For purposes of reference, the transverse horizontal center line of the machine is assumed to be the upper for-

ward edge of the flange 16, or any line parallel thereto in the same vertical plane.

Secured on the shaft 50 are a pair of distorting rolls 68 and 70 which in longitudinal section are concave. These rolls are both alike, each comprising a metal core 72 (Fig. 6) secured by a set screw to the shaft 50 and a thick rubber cushion 74 secured by a bonding layer 76 to the core 72. The cushion 74 is of substantially uniform thickness, the concave form of the roll being determined by the periphery of the core 72.

Mounted above the roll 68 to cooperate therewith is a distorting roll 78 which is convex in longitudinal section, having a contour which is substantially complementary to that of the roll 68. A distorting roll 80 similar in all respects to the roll 78 is mounted above and in cooperative relation to the roll 70. The rolls 78 and 80 are each mounted for up and down swinging movement and are each resiliently pressed toward their cooperating rolls 68 and 70, respectively, by mechanisms which will now be described. The mechanisms for each of the rolls 78 and 80 are similar, and for convenience the same reference characters will be employed to designate the corresponding parts of the two mechanisms. It should be understood, however, that these two mechanisms are independent of each other. The roll 80, as shown in longitudinal section in Fig. 6, is of hollow metal construction and is journaled upon two sets of ball bearings 82 and 84 supported upon a horizontal stud 86 extending from a lever 90. Secured in the unsupported end of the stud 86 is a stationary cover plate 82 for the adjacent end of the roll 80. The lever 90 is provided with a hub 94 by which the lever is pivotally mounted upon a stationary shaft 96 extending between the end plates 32 and secured thereto by set screws 98. Threaded in a boss 100 (Figs. 4 and 6) extending upwardly from the crosspiece 34 is a screw 102 having a knurled head 104. Interposed between the head 104 and a horizontal flange 106 formed on the lever 90 is a spring 108 surrounding the shank of the screw 102. The compression of the spring 108 may be varied by turning the head 104. The boss 100 serves as an abutment for the flange 106 to limit downward movement of the lever 90 and thereby to maintain a slight clearance between the rolls 70 and 80 when no work is passing between them. The roll 78, as has already been pointed out, is similar to the roll 80 and is similarly supported, and the various members associated with the roll 78, in so far as they are shown in the drawings, are indicated by the same reference characters as the corresponding members associated with the roll 80.

Secured upon the crosspiece 34 is a work support 110 upon which soles may be fed to the above-described rolls. The work support 110 has a work-guiding partition 112 which extends between the adjacent ends of the rolls 68 and 70. The support 110 is provided also at each of its ends with an upright guide plate 114. For supporting the soles as they leave the deforming rolls there is provided a table 116 carried by the crosspiece 36. Positioned above the table 116 is a guide 118 (Fig. 4) pivotally mounted for swinging movement of adjustment about a pin 120 extending between the plates 30 and 32 and secured therein by set screws 122. Extending between the plates 30 and 32 and journaled in suitable bearings formed therein is a shaft 124 parallel to the distorting roll shaft 50. Mounted upon the shaft 124 are a plurality of toothed wheels 75

126 which engage the under surface of the soles as they leave the table 116 and feed the soles toward the abrading roll. The guide 118 has a smooth under surface which engages the soles 5 and holds them down in contact with the teeth of the feed wheels 126. The toothed wheels 126 are spaced from each other by collars 128 (Fig. 5). The shaft 124 has a gear 130 (Fig. 12) secured upon one of its ends and driven by an idler gear 132 mounted upon a stud secured in the plate 30. The idler gear 132 is in turn driven by a gear 134 secured upon the end of the shaft 50. The gears 132 and 134 are housed in a casing 136 secured upon the end plate 30 and having a removable cover 138.

A buffing roll 140, which may be of any well known construction, is secured upon a shaft 142 mounted in bearings 144 and 146 and having its axis parallel to the transverse horizontal center line of the machine. For an example of a suitable buffing roll reference may be had to a co-pending application for Letters Patent of the United States Serial No. 232,123 filed in my name September 28, 1938 as a division of this application. The bearing 144 is secured upon the plate 14 of the machine head and the bearing 146 is secured upon a bracket 148 (Fig. 1). One end of the bracket 148 is secured upon the outer end portion of the flange 16. The opposite end 20 of the bracket 148 is secured upon an upright post 150 interposed between the end portions of a forwardly and rearwardly extending tie rod 152 and a transverse tie rod 153, the two tie rods and the post 150 being rigidly secured together 25 by screws threaded into the end of the tie rod 153. The opposite ends of the tie rods 152 and 153 are secured to the plates 24 and 20, respectively. A supporting post 154 extending from the base 12 is secured to the tie rod 153 adjacent 30 to the post 150. The buffing roll 140 is driven in the direction of feed of the work but at a considerably greater peripheral speed, by a pulley 156 mounted upon the shaft 142 and driven by a belt 388. The driving arrangements for the belt 388 will be described later.

The work is pressed against the buffing roll and is fed while in engagement therewith by a mechanism comprising a plurality of feed belts 214 (later to be more fully described) arranged 35 in side-by-side relation and supported on idler pulleys. This mechanism, as shown in Figs. 1, 7 and 8, is carried by a pair of parallel arms 158 and 160 which are mounted for free swinging movement in unison about a stationary shaft 162 secured at its ends in the bracket 152 and the plate 20. The free ends of the arms 158 and 160 are rigidly connected by a crosspiece 170. Passing loosely through an opening in the crosspiece 170 and pivotally mounted at one of its ends upon 40 a bracket 172 supported by the plate 124 is a rod 174. A nut 176 is threaded on the free end of the rod 174. Interposed between the nut 176 and the crosspiece 170 is a compression spring 178 which tends to swing the arms 158 and 160 upwardly to press the work against the buffing roll. Threaded into the mid-portion of the crosspiece 170 is a pin having a head 180 which engages the under edge of the plate 24 as a stop to limit upward movement of the work-pressing and feeding mechanism under the influence of the spring 178, and thereby to maintain clearance between the buffing roll and the work-pressing and feeding members when no work is passing therebetween. A compression spring 182 surrounds the above- 45 mentioned pin and is interposed between the

head 180 and the crosspiece 170 to prevent undesired turning of the pin, thus maintaining the pin in any desired position of adjustment.

The feed belts 214 and their supporting idler pulleys are carried by brackets 184 and 186 mounted on the arms 158 and 160, respectively. The brackets 184 and 186 are similar to each other and are in the form of a pair of spaced parallel vertically disposed plates having horizontally extending ears 188 whereby the brackets 10 are secured to lugs 189 on their respective arms 158 and 160.

The feed belt mechanism carried by the brackets 184 and 186 will now be described. As shown in Fig. 8, there is provided a horizontal stationary shaft 190 having formed along its length a plurality of spaced collars 191. Each of the collars 191 has a peripheral surface which is spherical and which has its center in the axis of the shaft 190 and at the mid-section of the collar. Mounted upon each of the collars 191 is a disk 192 having an internal cylindrical bearing surface which engages the periphery of the collar. Each of the disks 192 carries upon its periphery a flanged bearing ring 193 of anti-friction material upon which is rotatably mounted an idler pulley 194 for supporting one of the feed belts 214. Beyond each of the end disks 192 is a wedge-shaped end plate 195. These end plates 195, when assembled on the shaft 190 as 20 shown in Figures 8 and 9, have vertical surfaces which are parallel to each other and inclined at a horizontal angle of 85° from the axis of the shaft 190, and it is these inclined surfaces which engage the end disks 192. Extending into a counterbore formed in each end of the shaft 190 is a flanged cup-shaped clamping member 196, the adjacent end plates 195 being counterbored to receive the flanges of the cups. Extending axially through the base of each clamping member 196, and threaded axially into each end of the shaft 190 is a clamping screw 198. When the screws 198 are tightened the flanges of the cups exert clamping pressure through the end plates 195 and all the disks 192 and bearing rings 193, binding them all into a rigid unitary assembly. The pulleys 194 are slightly thinner than the disks and bearing rings which support them, and are accordingly free to rotate on their bearing rings. The unitary assembly is secured 25 to the brackets 184 and 186 by screws 200 passing through the brackets and threaded into the respective end plates 195. When the various parts are thus assembled the axis of the shaft 190 will be parallel to the transverse horizontal center line of the machine, and the pulleys 194 will all have their axes parallel to the axis of the distorting roll shaft 50 and inclined at angles of 5° from parallel to the axis of the buffing roll 140.

The mechanism for driving the feed belts 214 is carried by a bracket 204 extending substantially parallel to the shaft 190. The bracket 204 is secured at its opposite ends by bolts 206 threaded into feet 202 which depend from the 30 brackets 184 and 186 respectively. The bolts 206 extend through vertical slots in the bracket 204, thereby providing for up and down adjustment. Journalized in suitable bearings formed in the ends of the bracket 204 is a shaft 208 upon 35 which is mounted a multiple pulley 210 having as many peripheral grooves 212 as there are pulleys 194, of which there are sixteen in the illustrated machine. Engaging each of the grooves 212 and extending around the corresponding 40

- pulley 194 is one of the feed belts 214. As shown in Fig. 7, the walls of each of the grooves 212 are inclined and the portion of the belt 214 which engages the walls 212 is correspondingly tapered, the tapered portion, however, being truncated, and the walls of the groove being sufficiently narrow to prevent the belt from seating in the bottom of the groove. The walls of the grooves of the pulleys 194 are likewise inclined to accommodate the tapered portions of the belts 214 but are sufficiently wide to enable the belts to seat in the bottom of the grooves. The portions of the belts 214 which extend out of the pulley grooves are rectangular in cross section.
- 15 The belts 214 are composed of a resilient rubber composition material and may be of the type disclosed in United States Letters Patent No. 1,662,511, granted March 13, 1928 on the application of Walter Geist.
- 20 Secured upon an end of the shaft 208 is a worm wheel 216 which is driven by a worm 218 secured upon a shaft 220 which is mounted in suitable bearings formed in a housing 222. The housing 222 is secured by screws 224 to the adjacent end of the bracket 204 and is provided with cover plates 226 and 227 to provide access to the gears. Secured upon the shaft 220 is a pulley 228 (Figs. 1 and 2) driven through a belt 402 by means which later will be described.
- 25 Positioned in advance of the buffing roll 140 is a plate 232 (Fig. 4) having a smooth work-engaging under surface disposed tangentially with respect to the buffing roll 140 and extending as close thereto as practicable, the upper edge of the plate 232 being beveled to provide clearance for the buffing roll. The plate 232 is secured upon a bracket 230 by a screw 233 and may be adjusted horizontally toward and from the buffing roll. The bracket 230 is provided with heightwise adjusting screws 234 bearing against the upper surface of the plate 24 and is clamped against the plate 24 by screws 236 extending through vertical slots in the bracket 230.
- 30 Beneath the plate 232 is a table 238 positioned to receive the work which has passed over the feed roll 126 and to support the work on its passage to the buffing roll. Secured to the plate 238 are end pieces 240 of sheet metal for guiding the work in the direction of feed. The plate 238 is secured for adjustment in the direction of feed to a bracket 242 having a depending vertical flange 244 which, in turn, is clamped against a vertical flange 246 (Fig. 5) extending from a crosspiece 248 secured with provision for heightwise adjustment by screws 250 to the end plates 30 and 32.
- 35 It will be noted that the work-piece has been fed to the buffing roll 140 in a plane which is substantially tangent to the buffing roll. The feed does not continue in that plane, however. After leaving the feed belts 214 the work-piece is still maintained in engagement with the buffing roll, about which it curves, for further buffing action before leaving the roll. The instrumentalities for effecting this further treatment serve also to guide the work to a mechanism for cleaning off the dust which arises from the operation of the buffing roll. These instrumentalities and the cleaning mechanism are carried by a common supporting structure which will now be described. Secured upon the rear end of the crosspiece 152 (Fig. 1) is an upstanding L-shaped bracket 252. A similar bracket is likewise secured upon a flange extending horizontally from the rear portion of the plate 20. Se-

cured to the upright portion of these brackets is a bracket having a pair of vertically disposed end portions 256 for engaging its supporting members and having an intermediate portion 258 which is inclined forwardly and upwardly at an angle of about 30° to the vertical. Clamped against the inner face of the inclined portion 258 is an L-shaped bracket 260 having at its upper end a flange 262 which is inclined forwardly and downwardly at an angle of about 30° to the horizontal. Clamped against the upper face of the flange 262 is a plate 264. It should be noted that in the arrangements for securing the bracket 256 to its support provision is made for heightwise adjustment, such provision likewise being made in the arrangements for clamping the bracket 260 to the inclined intermediate portion 258 of the bracket 256. Heightwise adjustment of the bracket 260 is facilitated by a screw 263 engaging the lower edge of the bracket 260. Provision is also made for adjusting the plate 264 along the direction of feed upon its support 262. The plate 264 is secured upon its support 262 at an angle of about 5° from the horizontal center line of the machine.

20 The instrumentalities for maintaining the sole in engagement with the buffing roll after its initial contact therewith comprise a pair of presser or deflector plates 284 and 286 (Figs. 9 and 10). The reason for providing two of these presser plates is to enable the presser plates to handle soles independently when fed two at a time in side-by-side relation. These presser plates, as shown in Fig. 11, engage the under surfaces of the soles after the latter have left the feed belts 214, and deflect the soles upwardly, curving them about the buffing roll and maintaining them lightly pressed against the buffing roll. The presser plates 284 and 286 are yieldingly mounted upon a plate 288 which, in turn, is secured by a pair of angular brackets 290 to the plate 264. The yieldable mounting of the plates 284 and 286 is best shown in Fig. 10 and is accomplished by means of screws 292 having heads which set in counterbored holes in lugs 294 extending from the plates 284 and 286. In order to prevent rotation of the screws 292 the heads of these screws are provided with projections 296 (Fig. 9) which seat in suitable recesses formed in the counterbores for the screw heads. The shanks of the screws 292 extend downwardly through openings in the plate 288. Threaded upon the lower end portions of the screws 292 are knurled heads 298 which may be turned to adjust the compression of springs 300 interposed between the heads of the screw and the plate 288. As shown in Fig. 10, the under surface of each of the plates 284 and 286 is in the form of an obtuse dihedral angle to enable the plates to rock upon the plate 288 as the springs 300 yield, the extent of such rocking, however, being limited by screws 302 threaded through the plate 288 and engaging the plates 284 and 286. Undesired rotation of the screws 302 is prevented by springs 304 interposed between the heads of the screws 302 and the under surface of the plate 288. The plates 284 and 286 each have a beveled surface 305 (Fig. 11) which engages the leading ends of the soles and deflects the soles upwardly against the buffing roll, against which they are pressed by an upper surface 307 of each of the plates. The under corners of the plates 284 and 286 are beveled off, as indicated by the reference character 309, to clear the feed belts 214. The soles travel along the surface 307 and then continue along the

upper surface of the plate 288 at an upward inclination of 30° to the horizontal until they engage a feed roll comprising a plurality of toothed wheels 306 spaced by suitable collars from each other along a shaft 308. Secured at each end of the plate 264 is a bearing 310 in which the shaft 308 is rotatably supported.

As has already been mentioned, the plate 264 is turned at an angle of about 5° from the transverse horizontal center line of the machine while the axis of the buffing roll is parallel to the transverse horizontal center line. The edge of the plate 264 is accordingly provided with a step to compensate for the resulting difference in the spacing of its ends from the buffing roll, the plate 288 being provided with a similar step. These steps are both indicated in Fig. 9 by the numeral 312. In securing the deflector plates 284 and 286 to the supporting plate 264 the edges of these deflector plates are parallel to the axis of the buffing roll. In order to provide for the greater spacing between the feed roll 306 and the deflector plate 286 there is provided an additional feed roll comprising toothed wheels 314 spaced by suitable collars and mounted on a shaft 316 extending parallel to the shaft 308. The shaft 316 extends only half the length of the shaft 308 and is journaled in bearings 318 mounted on the plate 264. The axes of the feed roll shafts 308 and 316 are inclined at an angle of 5° to the transverse horizontal center line of the machine and are parallel to the axes of the distorting roll shaft 50 and the feed roll shaft 124.

For pressing the work down against the feed roll 308 there are provided a pair of plates 320 and 322 (Figs. 9, 10 and 11) beveled at 324 to engage the leading ends of the soles. The plate 322 serves also to hold the work down against the additional feed roll 316. The plates 320 and 322 are beveled also at 325 to clear the buffing roll 140. The plates 320 and 322 are secured upon the free ends of a pair of arms 326 and 328, respectively, which are pivotally mounted upon pins 330 secured in brackets 332 mounted upon ears 334 extending rearwardly from the plate 264. In order to hold the plates 320 and 322 down with sufficient pressure there are provided a pair of stationary members 336 into each of which is threaded a screw 338. The members 336 consist of lugs extending from bearing supports later to be described. A compression spring 340 surrounds the shank of each of the screws 338 and is interposed between a head formed on the screw and a block 342 which is freely swiveled upon the arm 326 and through which the shank of the screw 338 passes with sufficient clearance to accommodate the swinging movement of the arm.

The cleaning mechanism will now be described. Secured upon one end of the plate 264 is a support 266 for a bearing 268 and secured upon the other end of the plate 264 is a support 270 for another bearing 272. It is from these supports 266 and 270 that the above-described lugs 336 extend. Journaled in the bearings 268 and 272 is a shaft 274 upon which is mounted a cylindrical cleaning brush 276. The shaft 274 is parallel to the distorting roll shaft 50. In order to provide for heightwise adjustment of the brush 276 the bearing 268 is clamped to its support 266 by a screw 278 passing through a vertical slot in the support 266, and a vertical adjusting screw 280 is threaded into the bearing 268 and has a flanged head bearing against

an abutment surface formed on the support 266. Each of the bearings is provided with a vertical tongue and groove connection to its support. The bearing 272 may be clamped in any desired position of vertical adjustment by a screw 273 extending through a vertical slot in the support 270 and threaded into the bearing 272. Mounted on the shaft 274 is a pulley 282 through which the brush 276 is driven at high speed in a direction opposed to the feed of the work. The pulley 282 is driven through a belt 398 by mechanism later to be described.

For supporting the soles while in engagement with the brush 268 there is provided a plate 344 secured to the plate 264 in parallel relation thereto by screws 346 and spacing collars 348. After the work has passed the cleaning brush it is engaged by a feed roll 350 comprising toothed wheels spaced from each other by suitable collars along a shaft 352 journaled at its ends in bearings 354 secured upon the plate 264. The feed roll 350 is parallel to the distorting roll shaft 50. For holding the soles down in engagement with the rolls 350 there are provided a pair of plates 356 secured upon arms 358, respectively, which arms are, in turn, pivotally mounted for swinging movement upon pins 360 secured in the brackets 332. No springs are necessary to hold the arms 358 down, their weight alone being sufficient to insure proper feeding of the sole at this point. The feed rolls 306, 314 and 350 are all driven from power supplied through a belt 361 to a pulley 362 secured upon one end of the shaft 352. Secured upon the opposite end of the shaft 352 is a gear 364 (Fig. 13) which drives an idler gear 366 which drives a second idler gear 367, which, in turn, drives a third idler gear 368. The idler gear 368 is in direct engagement with a pair of gears 370 and 372 secured on the shafts 308 and 316, respectively, for driving the feed rolls 306 and 314. The idler gears 366, 367 and 368 are mounted on stub shafts secured in a housing 374 for the gears 364 to 372, inclusive.

After leaving the feed roll 350 the soles drop into a box 376 (Fig. 1) supported upon a bracket 378 which is mounted upon the post 154.

The power for driving the various mechanisms above described is all transmitted through a main shaft 380 from any suitable source of power. The shaft 380 is mounted in self-aligning bearings 382 on supports 384 on the base 12 of the machine. Secured on the shaft 380 is a pulley 386 which drives the buffing roll pulley 156 through the belt 388. Suitable tension is maintained in the belt 388 by an idler pulley 390 (Fig. 1) mounted upon the free end of an arm 392 which is pivotally supported for free swinging movement upon a pin 394 secured in the frame.

Also mounted on the shaft 380 is a pulley 396 which drives the brush pulley 282 through the crossed belt 398. A third pulley 400 secured upon the shaft 380 drives the mechanism for feeding the work past the buffing roll through the belt 402 engaging the pulley 228. An idler pulley 404 is provided for changing the direction of the belt 402 between the pulleys 400 and 228. The idler pulley 404 is mounted on a bracket 406 secured on one of the supports 384 with provision for adjustment. Secured on the end 70 of the shaft 380 is a fourth pulley 408 which drives the distorting mechanism. A belt 410 carries the drive of the pulley 408 to a pulley 412 secured upon the end of a shaft 414. Secured upon the opposite end of the shaft 414 is 75

a pulley 416 which drives the pulley 62 through the belt 418. The shaft 414 is journaled in a bearing 420 supported by a bracket 422 secured upon the base 12 of the machine. The bracket 5 422 includes a pivotally mounted member 424 which may be clamped in any desired position of angular or lengthwise adjustment by a hand nut 426 on a bolt passing through a slot 428 formed in the member 424, thus enabling the 10 pulley 412 to be positioned to maintain suitable tension in both of the belts 410 and 418. The cleaning mechanism feed rolls are driven through the belt 361 by a pulley 430 on the shaft 208. An idler pulley 432 supported by a plate 15 434 adjustably mounted on a boss 433 (Fig. 2) formed on the tie rod 152 engages the belt 361 to maintain suitable tension therein.

In order to insure convenient disposition of the dust which arises from the operation of the 20 buffering roll upon the work there is provided a dust hood 436 connected to the usual exhaust system and having its opening extending over the locality in which the work leaves the buffering roll and over the cleaning brush. A cover plate 25 438 is also provided for enclosing the space above the buffering roll between the hood 436 and the flange 16. The cover plate 438 is hinged on pintles 440, and is held down by a winged nut 442. An extension 444 of the cover plate 438 30 is made adjustable to enable a minimum clearance to be obtained between the extension 444 and the forward wall of the hood 436. The cover plate 438 carries upper end walls 446. A stationary end wall 448 below the outer end wall 35 446 is also provided, as well as a front wall 450. The dust hood 436 communicates with the space beneath the cover plate 438, although a baffle is positioned close to the abrading roll 140 to prevent a peripheral current from developing 40 about the roll. The plate 232 is perforated to enable air to be drawn into the space beneath the cover plate 438 and thence into the dust hood.

The operation of the machine as so far described will now be explained. The soles to be 45 treated may have local variations of thickness resulting from a previous skiving or edge beveling operation, from the thickening of the edge portions resulting from a previous edge setting operation, and from other causes. The soles are introduced by the operator alternately between the two sets of distorting rolls 68, 50 78 and 70, 80 which impart to the soles a transverse curvature which they tend temporarily to retain. The fact that the lower concave driven rolls 68 and 70 are covered with a cushioning 55 layer of rubber not only insures that these rolls will feed the work but also insures that the upper surfaces of the soles will assume a curvature complementary to that of the convex metal rolls 78 and 80 inasmuch as the cushioned surfaces of the rolls 68 and 70 will yield to accommodate whatever local variations of thickness there may be in the soles. It should be 60 noted that the doubly convex metal rolls will tend to impart a lengthwise as well as a transverse curvature to the soles. After passing the distorting rolls the feed of the soles is continued by the roll 126. As the leading ends of the soles 65 70 come into engagement with the feed belts 214 the soles are pressed against the plate 232, the upper surfaces of the soles being thereby flattened while all the local variations of thickness are accommodated by the resilient feed belts 75 214. As the soles pass the edge of the plate 232

in this flattened condition they immediately engage the buffering roll 140. If the soles have skived or beveled edges it is evident that the pressure exerted by the feed belts 214 through these edges will be less than the pressure exerted 5 through the relatively thicker material in the central portions. However, the tendency above mentioned of the soles to retain the curvature imparted to them by the distorting rolls will offset, at least in part, the diminution of pressure exerted by the feed belts through the thinner marginal portions. The upper surface of a sole will thus be presented with substantially uniform pressure across its entire width to the buffering roll. 10 15

The inclination of the axis of the pulleys 194 relatively to the axis of the buffering roll will cause the feed belts 214 to impart to the work a feeding movement which has a lengthwise component relatively to the buffering roll. This lengthwise component serves to efface scratch marks which might otherwise appear upon the surface of the work. These scratch marks result from particles of grit projecting above the general level of the abrasive surface and gouging out fine 25 lines upon the surface of the work. For each revolution of the buffering roll the sole advances only a relatively slight distance in the course of its feed and, if it were not for the above-mentioned component, the same particle of grit would 30 gouge more deeply into the line already formed and would also extend the line. This would occur indefinitely and the result would be a long deep conspicuous scratch mark. However, because of the lateral displacement of the work-piece resulting from the lengthwise component of the feeding movement the successive scratch marks of any unduly prominent particle of grit 35 will be laterally displaced from each other in the form of a series of relatively short, shallow, parallel lines so close together that they merge and 40 become invisible. The lateral displacement of the work-piece, moreover, subjects the already formed scratch marks to the erasing action of the normal area of the abrasive surface adjacent to the projecting particle. 45

The passage of a sole S past the buffering roll is shown in Fig. 11. As the sole advances between the buffering roll and the feed belts its leading edge engages the bevel 305 on the presser plate 307, deflecting the sole upwardly and prolonging its engagement with the buffering roll against which it is held with relatively light pressure, as compared with the pressure of the feed belts, by the springs 300. Such curving of the sole about the buffering roll is facilitated by the tendency to longitudinal curvature, already mentioned, which has been imparted to the soles by the distorting rolls. Thus, instead of merely engaging the buffering roll in a single plane of tangency it will be observed that the sole is curved 55 partially about the abrading roll and is subjected to a continued buffering operation under lighter pressure which tends further to obliterate any scratch marks which may have resulted from the initial contact of the sole with the buffering roll. Another advantageous effect of curving the sole and prolonging its contact with the buffering roll is to eliminate any tendency toward the formation of ripple marks which frequently occur 60 when the abrading action takes place along a limited area of tangency. 65

As the soles continue their leading edges engage the bevel 324 of the plate 320. The feed roll 306 (and also on the left-hand side of the 70 75

machine the feed roll 314) carry the soles forward over the plate 344 and in engagement with the swiftly rotating brush 276 which removes the dust caused by the action of the buffing roll. As the soles advance beyond the feed roll 350 they fall into the receptacle 378.

While the above described machine is intended primarily for the treatment of soles, it of course may be employed for the buffing of similar articles such as counters or box toe pieces which, like soles, may be flat or may have skived margins.

Having thus described my invention, what I claim as new and desire to secure by Letters 15 Patent of the United States is:

1. An abrading machine comprising a cylindrical abrading roll, a plurality of driven rotary feed members spaced lengthwise of said roll and constructed and arranged to hold a work-piece 20 against the roll, and a support for maintaining the axes of said feed members substantially parallel to each other in a plane parallel to the axis of the abrading roll and in a direction inclined to the axis of the abrading roll.

2. An abrading machine comprising an abrading roll engageable with one surface of a work-piece of sheet material, a plurality of belts engageable with the opposite surface of the work-piece at the locality engaged by said abrading 30 roll, means for guiding said belts at their locality of engagement with the work-piece in a direction inclined to the direction of movement of the surface of the abrading roll at said locality, and means for driving said belts in said guiding means 35 to cause said belts to feed the work-piece past the abrading roll.

3. An abrading machine comprising an abrading roll engageable with one surface of a work-piece of sheet material, a plurality of feed members spaced lengthwise of said abrading roll and engageable with the opposite surface of the work-piece at the locality engaged by the abrading roll, means for guiding said feed members at their locality of engagement with the work-piece in a direction inclined to the direction of movement of the surface of the abrading roll at said locality, a frame supporting said guiding means and pivotally mounted for swinging movement of the guiding means toward and from the abrading roll, and resilient means acting upon said frame to cause the feed members to press the work-piece against the abrading roll.

4. A work-feeding mechanism for an abrading machine comprising a plurality of pulleys, means for supporting said pulleys with their centers in a straight line and their axes inclined to said straight line, a work-engaging belt on each of said pulleys, and means for driving said belts to cause them to impart to a work-piece a feeding movement which by reason of the inclination of said axes has a component along said straight line, thereby enabling said belts to engage a work-piece tangentially along a straight line and to feed the work-piece in a direction inclined to said line of engagement.

5. A work-feeding mechanism for an abrading machine comprising a plurality of idler pulleys, a multiple driving pulley having a belt groove for each of said idler pulleys, a work-engaging belt between each of said grooves and its corresponding idler pulley, and means for supporting said idler pulleys for rotation about axes parallel to each other and inclined to the direction of the axis of the driving pulley, the line of centers of the idler pulleys being parallel to the axis of the

driving pulley, whereby the belts are enabled to engage a work-piece along a line of tangency and to feed the work-piece in a direction inclined to said line of tangency.

6. A work-feeding mechanism comprising a 5 plurality of curved belt guides arranged side-by-side and tangent to a common plane, said guides having their points of tangency with said plane disposed all in the same straight line, said guides also at their intersections with said line being 10 all parallel to each other and extending in a direction inclined from the perpendicular to said straight line, and means for driving said belts in said guides to impart to said belts a work-feeding movement which by reason of said inclined 15 direction of said guides will have a component along a line of tangential engagement with a work-piece.

7. An abrading machine comprising an abrading roll engageable with one surface of a work-piece of sheet material, means engageable with the opposite surface of the work-piece for pressing the work-piece against the abrading roll, driven feed rolls engageable with the work-piece on each side of the abrading roll and having their axes parallel to each other and inclined to the direction of the axis of the abrading roll, means for holding the work-piece in engagement with said feed rolls, and means for imparting to said pressing means a feeding movement which is at 30 right angles to the direction of the axes of said feed rolls.

8. A buffing machine comprising a buffing tool, means for feeding a work-piece past said buffing tool, means for holding the work-piece with a relatively heavy initial pressure against said buffing tool, and means engageable with a portion of the work-piece which has already passed said holding means for holding the work against said buffing tool with relatively lighter 40 pressure.

9. A buffing machine comprising a buffing roll engageable with one surface of a flexible work-piece, feeding means engageable with the opposite surface of the work-piece constructed and 45 arranged to hold the work-piece against the buffing roll with relatively heavy pressure, and a presser engageable with said opposite surface of the work-piece at a locality which has passed said feeding means for holding the work-piece 50 against the buffing roll with relatively lighter pressure.

10. A buffing machine comprising a buffing roll engageable with one surface of a work-piece of sheet material, means engageable with the opposite surface of the work-piece for feeding the work-piece and pressing the work-piece against the buffing roll, a deflector plate engageable with said opposite surface of the work-piece beyond 55 said feeding means, and resilient means acting upon said deflector plate to cause the deflector plate to press the work-piece against the buffing roll.

11. A buffing machine comprising a buffing roll engageable with one surface of a flexible work-piece, feeding means engageable with the opposite surface of the work-piece constructed and arranged to press the work-piece against said buffing roll, a feed roll displaced along the line of feed from said feeding means, means for 70 holding the work-piece against said feed roll, and means for pressing the work-piece against the buffing roll at a locality between said feeding means and said feed roll.

12. A buffing machine comprising a buffing 75

- roll, means for feeding a work-piece past said buffing roll, additional work-feeding means beyond said buffing roll, and means for guiding the work-piece to said additional feeding means, said 5 guide means being constructed and arranged to curve the work-piece about the buffing roll.
13. A machine for buffing skived soles comprising a buffing roll, means positioned in advance of said buffing roll for imparting to a sole a trans- 10 verse curvature, a cleaning mechanism positioned beyond the sole for removing from the sole dust resulting from the operation of the buffing roll on the sole, means for feeding the sole lengthwise past said curvature-imparting means, said buff- 15 ing roll and said cleaning mechanism, and means for guiding the sole from said curvature-imparting means to said buffing roll and from said buffing roll to said cleaning mechanism, said guide means being constructed and arranged to 20 curve the sole about the buffing roll to increase the area of contact.
14. A machine for buffing skived soles comprising a buffing roll, means positioned in advance of said buffing roll for imparting to a sole a trans- 25 verse curvature, a cleaning mechanism positioned beyond the sole for removing from the sole dust resulting from the operation of the buffing roll on the sole, and means for feeding the sole lengthwise past said curvature-imparting means,
- 30 said buffing roll and said cleaning mechanism, the axis of said buffing roll forming an acute angle with a line perpendicular to the direction at which the sole is advanced by said feeding means.
15. A device for imparting to a skived sole a transverse curvature to prepare the sole for buffing, comprising a roll of concave curvature longitudinally and having a yieldable periphery adapted to engage one surface of a sole, a roll of substantially complementary convex curvature longitudinally and having a hard periphery, means for driving said concave roll, and yieldable means for urging one of said rolls toward the other to cause the rolls to impart curvature to 10 a sole passing between them.
16. An abrading machine comprising an abrading roll, a plurality of pulleys spaced lengthwise of said roll, a belt running over each of said pulleys, said pulleys being arranged to cause said 15 belts to press a work-piece against the abrading roll, means for driving said belts to cause the belts to feed the work-piece past the abrading roll, and means for supporting said pulleys with their axes parallel to each other and inclined to 20 the lengthwise direction of the abrading roll to cause the feeding movement of the belts to take place in a direction having a lengthwise component relatively to the abrading roll.
17. A buffing machine comprising a buffing 25 roll, pressing members for holding a flexible work piece curved against and partially around said roll, means for feeding the work piece in such state of curvature past the roll, and means positioned in advance of the buffing roll for imparting 30 to the work piece a tendency to curve about the buffing roll.

NORWOOD H. KNOWLTON.
